UNITED STATES PATENT OFFICE.

WALLACE R. KIRK, OF KANSAS CITY, MISSOURI.

RAILWAY-SIDING.

SPECIFICATION forming part of Letters Patent No. 474,665, dated May 10, 1892.

Application filed July 11, 1891. Serial No. 399,144. (No model.)

To all whom it may concern:

Be it known that I, WALLACE R. KIRK, of Kansas City, Jackson county, Missouri, have invented certain new and useful Improvements in Railway-Sidings, of which the following is a full, clear, and exact description, reference being had to the accompanying drawings, forming a part hereof.

My invention relates to the construction of railway-sidings; and the object of my invention is to produce a siding for railway-tracks which are laid in alley-ways and similar confined narrow or otherwise-restricted places, and by means of which one or more cars of freight or other railway trains can be readily side-tracked from the main line in such manner as not to obstruct the alley-way nor the main track.

To the above purpose my invention consists in certain peculiar and novel features of construction and arrangement, as hereinafter described and claimed.

In order that my invention may be fully understood, I will proceed to describe it with reference to the accompanying drawings, in which—

Figure 1 is a perspective view of a railway-siding constructed in accordance with my invention, the main line being in condition for the passage of trains and certain parts being partially broken away to more clearly disclose the construction. Fig. 2 is a plan view of the same, certain parts being partially broken away to more clearly disclose the construction. Fig. 3 is a plan view of the same, the siding being out of alignment with the main line, as when supporting a shunted car. Fig. 4 is an irregular vertical longitudinal section on the line 44 of Fig. 1. Fig. 5 is a transverse vertical section on the line 55 of Fig. 2. Fig. 6 is an irregular transverse vertical section on the line 66 of Fig. 3. Fig. 7 is a transverse vertical section on the line 77 of Fig. 2. Fig. 8 is a detached perspective view of one of the movable ties for the movable main-line section.

Previous to my invention it has been impossible to provide sidings in narrow alley-ways between warehouses and similar structures, and consequently in many instances such warehouses are deprived entirely of railway facilities, and their occupants are obliged

to endure the delays and expense of teaming in order to load their goods upon and unload them from railway-cars. As will be seen from 55 the ensuing description, I have devised means whereby one or more cars can be readily detached from a train in a narrow alley-way and side-tracked in such a manner that the shunted car shall in no way obstruct either 60 the main line or the alley-way, and so, also, that the cars shall occupy the most advantageous position for discharging and receiving their loads.

Referring now to the accompanying drawings, 1 designates the walls of two warehouses, factories, or other similar buildings, the space 2 between said walls being a narrow alley or driveway, such as is frequently found in manufacturing or commercial districts. 3 70 designates the permanent or main-line rails of a railway laid through said alley or driveway 2, and the proportions illustrated are those which generally exist between a railway of the usual standard gage and an ordinary alley or driveway of the kind described. From an inspection of the drawings it will be seen that it would be impossible to lay an ordinary "spur" of "siding" in the space intervening 80 between the adjacent walls 1 of the opposite buildings, and that none of the other various resources of railway engineering would avail to enable cars to be shunted off of the main track and not obstruct the alley or driveway 2. In order to accomplish this result, I provide the 85 alley or driveway 2 with one or any number of suitable pits 3^a, (see Figs. 4, 5, 6, and 7,) each of which is of suitable depth and which extends transversely of the alley or driveway from near the outer line of the wall 1 of one 90 building beyond the adjacent wall of the opposite building and into the latter a distance somewhat greater than the width of a car. This pit may be of a width somewhat greater than the length of a single car or somewhat greater than the length of several cars, as preferred, and in the bottom of this pit are laid a number of ties or sleepers 4, of any suitable or preferred kind, said ties or sleepers extending, preferably, transversely of the pit and being laid from one end of said pit to the other. Upon the ties 4 in that end of the pit which terminates outside of the wall 1 of one building are laid a number of fixed

or stationary stringers 5, which extend parallel with each other and longitudinally of the pit, and upon these stringers are laid two movable rails 6 and 7, which extend transversely 5 of the pit and which are moved into and out of alignment with the main-line rails 3, as hereinafter fully described. These two rails 6 and 7 are immediately supported by two or more movable tie-bars 8, (see, also, Fig. 8,) the base of the rail 7 being embraced by a chair 9 at the outer end of each tie-bar 8, and the outer side of the base of the rail 7 being engaged at times by a projection or half-chair 10 upon the corresponding end of each of said ties, or, in other words, upon the opposite end 15 from that which carries the chair 9. These two or more tie-bars 8 each move upon one of the stringers 5 just described.

Upon the ties 4, which are not covered by 20 the stringers 5, are laid two or more rails 11, which extend parallel with each other and longitudinally of the pit, and upon these rails run four or more truck-wheels 12, which support a movable platform 13, said platform 25 corresponding in length with the width of the pit and of a width somewhat greater than the space between the two main-line rails 3. Upon this platform 13 are placed and immovably secured two rails 14, which extend 30 parallel with each other longitudinally of said platform, and the space between which corresponds exactly with the space between the main-line rails 3; or, in other words, the "gage" of the rails 14 upon the platform 35 13 is the same as the gage of the main-line rails 3. Within the pit at points between the main-line tracks 3 are located four pulley-wheels 15, which are disposed in two pairs, each of said pairs of pulleys being so 40 located as to be at one end of the platform 13 when it is in the position shown in Figs. 1, 2, 5, and 7. In each of the corners of that end of the pit which enters one of the buildings is placed a pulley-wheel 16, preferably journaled in a guard-frame 17, and midway of each end of the pit are placed two pulley-wheels 18. Two chains 19 are connected, each at one 45 end to one side of the platform 13 midway of its length, and said chains extend thence oppositely over the two middle pulleys 18, also over the two corner pulleys 16, and also around the two corresponding pulleys 15, the ends of these chains extending upward to the surface of the alley or driveway, as shown. A pair of 50 chains 20 extend over two opposite pulleys 15 from those engaged by the chains 19 and thence around two corner and middle pulleys, (not shown,) but corresponding with the pulleys 16 and 18, just described, and the opposite ends of these chains 20 are secured to the opposite side of the platform 13 from that to which the chains 19 are secured. The outer ends of these chains 20 extend upward to the surface of the alley or driveway similarly as 55 do the chains 19, before described. The rails 14 of the platform 13 rest upon ties 21, which are so arranged as to alternate with the string-

ers 5, before described, and the operation of the mechanism thus far described is as follows: When a car is to be side-tracked, the 70 train is pushed or pulled by the engine and brought to a standstill with the car to be side-tracked standing upon the rails 14, said rails being, of course, in the position shown in Figs. 1, 2, and 6, or, in other words, in alignment with the rails 3 of the main line. The 75 car is now uncoupled from the train, at one end only if at one end of the train and at both ends if in the body portion of the train, and that portion of the train to which the engine is coupled is drawn away. Before this portion of the train is moved away the free end of one of the chains 19 is connected to the coupling of the end car of the train, and as said car moves it draws the platform 13 to 80 that end of the pit which enters the building, and thus carries the car sidewise into said building. As the rails 14 are thus moved away from the main-line rails 3 the outer rail 14, acting through a chain 21 or other flexible 85 connection, draws the adjacent rail 7 with it until said rail 7 comes into alignment with the main-line rails 3, which are next to the building into which the car is being carried. This movement of the rail 7, acting upon the tie-bars 8, causes the half-chairs 10 of said ties to engage the base of the companion rail 7 and draws said companion rail into alignment with the main-line rails which are farthest from the building into which the car has 90 been carried. Thus it will be seen that when the car has entered the building the main line is unbroken. The chain 19 can now be uncoupled from the car or engine and the latter backed down and coupled to the rest of 95 the train if the shunted car or cars were from the body of the train, and the train can proceed on its way. When it is desired to replace the car which has been side-tracked upon the main line, one end of one of the 100 chains 20 is coupled to the engine or to one of the cars of the train and the engine or car is moved upon the main line. This movement draws the rails 14 toward the main line, moving the ties 21 between the stringers 5 105 and first causing the advancing rail 14 to strike the rail 7, next to the building out of which the car is being drawn. This rail then strikes the companion rail 6, and both are moved out of line with the main-line rails 3, 110 as shown in Figs. 1, 2, 5, and 7, and the main line is closed by the rails 14, so that as soon as the car is coupled to the train it can be 115 drawn away.

In order to close the pit when the movable 120 rails 14 are in line with the main-line rails 3, a removable platform 22 may be placed upon that part of the pit which is in the building into which the movable rails are drawn at times, as above described, and in order to 125 cover the driveway or alley when the car is side-tracked a platform 24 is hinged adjacent to the wall of the building opposite from that into which the side-tracked car runs. This

platform is let down and covers the space between the rails 7. The two lower bars 25 of this platform 24 are pivoted at their ends into the two side pieces 26 of said platform and at 5 their corresponding ends each of these bars carries a gear-wheel 26^a, the teeth of said gear-wheels intermeshing. A lever 27 is pivoted upon this end of the upper bar and carries a pawl 28, which meshes with the teeth of 10 the corresponding gear-wheel. Thus before the platform is lowered the bars are turned a quarter of a revolution, so as to fit closely between the rails 7, as shown in Fig. 7. At the completion of the shunting movement of 15 the movable side-track rails 14 the movement of the movable rail 7 of the main line is arrested by a short chain or similar flexible connection 30, one end of which is secured to the outer side of the rail 7, while its opposite 20 end is secured stationarily to the ground, and the length of said chain being such as to arrest the movement of the rail 7 when it is in alignment with the corresponding main-line rails 3.

25 From the above description it will be seen that I have provided means whereby a car can be side-tracked in a confined space—such as an alley—without obstructing an alley-way or the main line, and also the mechanism employed can be readily and easily operated and 30 is simple and inexpensive in construction, and it will also be seen that these side-tracking and other described operations can be performed within the length of a single car, or 35 of two or more cars, as the case may be.

Having thus described my invention, what I claim as new therein, and desire to secure by Letters Patent, is—

1. An improved railway-siding comprising 40 a main line having a movable rail-section, a pair of movable side-track rails, and a pair of chains connected to said movable rails and serving to effect the required movements of the same, substantially as set forth.

2. An improved railway-siding comprising 45 a main line, a pair of movable side-track rails, a number of movable tie-bars, each permanently connected to one of said rails and having a projection to engage the opposite movable rail, a pair of movable main-line rails 50 connected with one of the movable side-track rails, and a pair of chains connected each side of the movable main-line-rail-supporting frame, substantially as set forth.

3. An improved railway-siding comprising 55 a main line having a movable track-section, a movable side track, and a hinged platform having a pair of rotating bars and a ratchet-gearing for operating said bars, substantially as set forth.

4. An improved railway-siding comprising 60 a main line having a movable rail-section, movable ties supporting said movable rail-section, a pair of movable side-track rails, and stationary stringers 5, supporting said side-track rails and alternating with said movable ties, substantially as set forth.

5. An improved railway-siding comprising 70 a pair of laterally-movable side-track rails, a pair of movable main-line rails connected by sliding ties, a flexible connection connecting the adjacent main-line rail and inner side-track rail, and a flexible connection connected to the outer movable side-track rail and to the ground, substantially as set forth.

6. An improved railway-siding comprising 75 a laterally-movable rail-section, a pair of movable side-track rails, and a pair of chains connected to the said movable rails and serving to effect the required lateral movements of the same, substantially as set forth.

In testimony whereof I affix my signature in presence of two witnesses.

WALLACE R. KIRK.
